UNITED STATES PATENT OFFICE.

GEORGE A. DAMON, OF CHICAGO, ILLINOIS, ASSIGNOR TO THE ARNOLD MAGNETIC CLUTCH COMPANY, OF MILWAUKEE, WISCONSIN, A CORPORATION OF WISCONSIN.

MAGNETIC CLUTCH.

No. 821,024.

Specification of Letters Patent.

Patented May 22, 1906.

Application filed April 15, 1903. Serial No. 152,682.

To all whom it may concern:

Be it known that I, GEORGE A. DAMON, a citizen of the United States, residing at Chicago, in the county of Cook and State of Illinois, have invented a certain new and useful Improvement in Magnetic Clutches, (Case B,) of which the following is a full, clear, concise, and exact description, reference being had to the accompanying drawings, forming a part of this specification.

My invention relates to improvements in magnetic clutches.

In devices of this character there is always a tendency of the members to remain clutched after the exciting-coil has been deenergized owing to residual magnetism. Various mechanical means have been devised to free the members simultaneously with the opening of the magnetizing-circuit; but no efforts have been made to overcome the residual magnetism other than to construct the parts of metal which will retain the least amount of magnetism.

The object of my invention is to destroy the residual magnetism within the members immediately upon deenergizing the coil which creates the same in order that the members may quickly separate. This is accomplished in the preferred form of my invention by providing two exciting-coils which will produce magnetic fields in proximity to each other having lines of force moving in opposite directions. When one coil is excited the other is deenergized, and the magnetic field of the excited coil will destroy the residual magnetism in the field of the other coil by reason of the lines of force of said fields moving in opposite directions and the magnetic field of the energized coil being stronger than the residual magnetism of the other field.

In the accompanying drawings the several views are as follows.

Figure 1 is a sectional elevation of my improved clutch. Fig. 2 is an end view thereof, and Fig. 3 is a view of my improved clutch in connection with a planer-bed.

In the drawings is illustrated one way of embodying my invention in a practical device. Therein is shown a shaft 1, on which is keyed a magnet member 2. The opposite faces of said magnet member are each provided with an annular channel 3, in

which is arranged windings 4. The currents in said windings 4 are caused to move in reverse directions, whereby the magnetic fields produced have lines of force which move in opposite directions, and the coils are so arranged that the fields produced by each have portions of their circuits in common. Each winding is preferably provided with a covering 5, placed in said channels. Upon the periphery of said magnet member are arranged, preferably, three collecting-rings 6, which are suitably insulated from said member and each other. As will be seen by reference to Fig. 3, the outer rings are each connected with one side of a different coil and the other sides of said coils are connected with the center collecting-ring.

One armature or member 7 is arranged opposite each side of the magnet member and preferably has a lead or zinc face 8, which meets with the magnet member. Said armatures are preferably supported by gear-wheels 9, to which they are bolted. The gear-wheels are loosely mounted on the shaft and are free to move independent of each other and the magnet member.

In Fig. 3 the clutch herein described is shown set for use in connection with a planer-bed. The shaft on which the members of the clutch are mounted is journaled in bearings 10 and has one end geared to a rack on a planer-bed 12. On a driving-shaft 13 are fixed gear-wheels 14, one of which meshes directly with one of the gear-wheels 9, and the other meshes with an idler 15, which meshes with the other gear-wheel 9. By this arrangement the armatures will be rotated in opposite directions, and the magnet member may be clutched to either one of them, according to the direction in which it is desired to move the planer-bed. The switch 16 for alternately closing the circuit through either of the windings may be connected with the planer-bed and operated thereby. In this manner the planer-bed may be shifted automatically by alternately connecting the magnet member with the oppositely-moving armatures.

The current is caused to flow through the windings in opposite direction, whereby the lines of force in the magnetic fields excited thereby move in opposite directions, as indicated by the arrows in Fig. 3. Only one coil

is energized at a time, and the magnetism of the field excited by the energized coil being stronger than the residual magnetism of the other field it destroys the residual magnetism. The residual magnetism being destroyed in the field of the magnet to which the armature is attached, said armature will be free to part from the magnet member, and the tendency which the members would otherwise have to remain clutched will no longer exist. Innumerable devices may be employed to open the circuit of one coil and close that of the other almost instantly, and thereby destroy the residual magnetism practically simultaneously with the deenergization of the exciting-coil of its field. In this way the magnet member may quickly have its movement reversed, for as soon as it is released from the armature with which it has been moving it may be clutched to the oppositely-moving armature.

It is immaterial of course which is the driving and which is the driven member, as they may be arranged to suit the circumstances.

25 Various changes may be made in the details of construction, arrangement, and combination of parts as herein shown and described without in any way departing from the spirit of my invention and the same yet 30 remain intact and be protected.

Having described my invention, what I claim as new, and desire to secure by Letters Patent, is—

1. In a device of the character described, a magnet member having exciting-coils adapted to produce magnetic fields with the lines of force of one field moving in an opposite direction to those of the other, whereby when one coil is energized its field will destroy the residual magnetism in the other field, substantially as described.

2. In a device of the character described, a magnet member having energizing-coils adapted to produce magnetic fields which have lines of force moving in opposite directions, the circuits of said fields having portions which are in common whereby when one coil is energized its field will destroy the residual magnetism of the other field, substantially as described.

3. In a device of the character described, a magnet member having energizing-coils adapted to produce magnetic fields which have lines of force moving in opposite directions, the circuits of said fields having portions which are in common, said coils adapted to be excited one at a time whereby the field excited by the energized coil will destroy the residual magnetism of the other field, substantially as described.

4. In a device of the character described, a magnet member having exciting-coils adapted to produce magnetic fields which have lines of force moving in opposite directions, the circuits of said fields having portions

which are in common, and means for alternately energizing said coils whereby the field excited by the energized coil will destroy the residual magnetism of the other field, substantially as described.

5. A machine of the character described, comprising a magnet member having exciting-coils, which will produce magnetic fields which have portions of their circuits in common, and means for causing the currents in said coils to move in opposite directions in order to excite magnetic field having lines of force which move in different directions, whereby when one coil is energized its field will destroy the residual magnetism of the other field, substantially as described.

6. In a device of the character described, the combination of an armature and a magnet member which are independently movable, said magnet member having exciting-coils adapted to produce magnetic fields which have their lines of force moving in opposite directions, the circuits of said fields having portions in common whereby when the exciting-coil of the magnet which attracts the armature is deenergized and the other coil energized, the magnetic field of the latter will destroy the residual magnetism in the field of the former and thus release the armature, substantially as described.

7. In a device of the character described, the combination with a pair of armatures, which are movable independently of each other, a magnet member arranged between said armatures, energizing-coils associated with said magnet member and each adapted to produce a magnetic field which will attract one of said armatures, said fields having lines of force moving in opposite directions and circuits with portions in common, whereby when one of said coils is energized its field will destroy the residual magnetism of the other field, substantially as described.

8. In a device of the character described, the combination with a pair of armatures, which are movable independently of each other, a magnet member arranged between said armatures, energizing-coils associated with said magnet member and each adapted to produce a magnetic field which will attract one of said armatures, said fields having lines of force moving in opposite directions and circuits with portions in common, and means for alternately closing the circuits of said coils whereby the field of the energized coil will destroy the residual magnetism of the other field, substantially as described.

9. A magnetic clutch comprising a pair of exciting-coils, one of said coils being arranged to destroy the residual magnetism of the other coil, said coils being adapted to be excited one at a time, substantially as described.

10. A magnetic clutch having a pair of exciting-coils connected in parallel and one part in common, said coils being adapted to pro-

duce magnetic fields with the lines of force of one field moving in an opposite direction to those of the other, said coils being adapted to be excited one at a time, whereby when one 5 coil is energized its field will destroy the residual magnetism of the other field, substantially as described.

11. In a magnetic clutch, a magnet member having two magnetic circuits, armatures 10 on either side of the magnet member, means for energizing either of the magnetic circuits and for thereby destroying the magnetism in the other magnetic circuit.

12. In a magnetic clutch, a magnet member having two magnetic circuits, armatures 15 on either side of the magnet member, means for energizing either of the magnetic circuits and thereby attracting one of the armatures and at the same time destroying the magnetism in the other magnetic circuit and releasing 20 the other armature.

13. In a magnetic clutch, a magnet member having two magnetic circuits, armatures 25 on either side of the magnet member, means for energizing either of the magnetic circuits and thereby attracting one of the armatures

and at the same time destroying the magnetism in the other magnetic circuit and releasing the other armature, and a driving-shaft geared directly to one of said armatures and 30 reversely to the other armature.

14. In a magnetic clutch, a driven shaft, a magnet member attached thereto, said magnet member having two magnetic circuits, armatures loosely mounted on the driven shaft 35 on either side of the magnet member, means for energizing either of the magnetic circuits and thereby moving one of the armatures into contact with the magnet member near its outer edge and at the same time destroying 40 the magnetism in the other magnetic circuit and releasing the other armature, and a driving-shaft geared directly to one of the armatures and reversely to the other.

In witness whereof I have hereunto subscribed my name in the presence of two witnesses.

GEORGE A. DAMON.
